UNITED STATES PATENT OFFICE.

FREDERICK BEE SANFORD, OF NORTH YAKIMA, WASHINGTON.

AMALGAMATOR.

No. 887,699.

Specification of Letters Patent.

Patented May 12, 1908.

Application filed September 13, 1906. Serial No. 334,423.

To all whom it may concern:

Be it known that I, FREDERICK B. SANFORD, a citizen of the United States, and a resident of North Yakima, in the county of 5 Yakima and State of Washington, have invented a new and Improved Amalgamator, of which the following is a full, clear, and exact description.

This invention has for its primary object 10 to provide means for treating auriferous wash by gravity unaided by mechanical force, and without reducing the ores to a finely pulverized pulp, as is necessary with the devices now in common use. This is accomplished by means of a receptacle having 15 a closed dividing cone formed centrally in the bottom thereof, and extending into a feed cylinder so as to divide the wash and deliver it by gravity pressure below the surface of a body of mercury placed within the receptacle in the manner more particularly 20 illustrated in the accompanying drawings, in which drawings like characters of reference indicate like parts throughout the views, and 25 in which

Figure 1 is a vertical central section of an amalgamator embodying my invention; and Fig. 2 is a horizontal section thereof taken on the line 2—2 of Fig. 1.

30 As illustrated in the drawings, a stationary receptacle 1 is provided with a central cone 2 extending upward from the bottom of the receptacle, preferably concave in outline, and having a closed upper end or dividing point 2^a projecting into the interior of 35 the body 3 of a feed cylinder. The lower end of said cylinder which extends into the receptacle 1 is formed with a flaring flange 4 making the end of the cylinder bell-mouthed, 40 so as to conform in outline to the cone and the bottom of the receptacle, and forming a vertically inclined annular passage-way between the cone and the flaring end of the cylinder, thereby allowing the material with- 45 in the cylinder to be divided and evenly projected into a body of mercury at the bottom of the receptacle. The flange 4 of the cylinder also serves to help support part of the material within the receptacle, and to prevent 50 said material from packing and obstructing the free passage of the material from the cylinder into the mercury at the bottom of the receptacle. By such means the material discharged through the feed cyl- 55 inder is projected into the receptacle beyond

the wall of the cylinder and thoroughly diffused with the mercury.

The lower end of the cylinder is held freely within the interior of the receptacle by means of supports 5 attached at one end to the receptacle, and provided on their upper end with nuts 5^a arranged preferably above and below lugs 3^a formed on the cylinder 3, whereby the feed cylinder may be adjusted relatively to the receptacle 1 and vary the width of the passage way between the cone 2 and the lower end 4 of the feed cylinder, as may be desired. The wash may be fed directly into the feed cylinder 3, or if desired an auxiliary section or elbow 6 may be attached 60 to the feed cylinder by means of an off-set flange 3^b engaging the end of the auxiliary section, and tie bolts 7 passing through lugs 3^c and 6^c formed on the feed and auxiliary cylinders and provided with clamping nuts 7^a. A pressure feed may be attached to the device, if desired, in cases where the water supply is limited and insufficient for sluicing 70 purposes. This device is preferably constructed of a conical hood 8 extending around the cone 2 of the receptacle, and spaced therefrom by means of bolts 8^a by which the hood is attached to the cone. The upper end of said hood is attached to a pipe 9 adapted 80 to be connected in any suitable manner to a water supply.

By means of this construction, auriferous wash, sand, gravel or other soluble matter may be passed from the sluice box into the feed cylinder 3, from whence the material 90 passes through the lower bell-mouthed end of the feed chamber into the bottom of the receptacle 1, where it becomes submerged in a suitable quantity of mercury and diffused therewith by gravity alone following 95 the lines of the outer surface of the cone 2.

Having thus described my invention, what I claim as new and desire to secure by Letters Patent is:

1. An amalgamator comprising a stationary receptacle provided with a central closed cone, a conical hood surrounding said cone and spaced therefrom, a water supply pipe connected with said hood, and a feed cylinder having an outwardly flaring lower 105 end inclosing said cone and hood, and spaced therefrom.

2. An amalgamator comprising a stationary receptacle provided with a central closed cone, a conical hood inclosing said 110

- cone and spaced therefrom, a water supply pipe connecting with said hood, a feed tube having an outwardly flaring lower end inclosing said cone and hood, and spaced therefrom to form a passage way, and adjusting mechanism connected with said receptacle and feed tube adapted to raise and lower said tube and vary the width of the passage way between the feed tube and receptacle.
- 10 3. In an amalgamator, the combination of a receptacle provided with a free upper edge and a closed central cone, a feed cylinder inclosing said cone and provided on its lower end with a flaring flange conforming in outline to that of the cone and spaced therefrom

so as to form a vertically inclined annular passage-way between the cone and lower end of the cylinder, terminating beyond the body portion of the cylinder, and means for adjusting said cylinder vertically relatively 20 to said receptacle and varying the width of said passage-way.

In testimony whereof I have signed my name to this specification in the presence of two subscribing witnesses.

FREDERICK BEE SANFORD.
